(57) **CLAIM**

I claim the ornamental design for a pair of slippers with
detachable upper, as shown and described.

DESCRIPTION

FIG. 1 is a top exploded perspective view of a pair of slippers
with detachable upper, showing the new design;

FIG. 2 is a bottom exploded perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

A slipper for a left foot is illustrated, it being understood that
the slipper for a right foot is a mirror image thereof.
